UNITED STATES PATENT OFFICE

96,640

DESIGN FOR A COMBINATION COAL AND GAS RANGE

Jesse W. Barker, Geneva, N. Y.

Application March 30, 1935, Serial No. 56,129

Term of patent 3½ years

To all whom it may concern:

Be it known that I, Jesse W. Barker, a citizen of the United States, residing at Geneva, county of Ontario, and State of New York, have invented a new, original, and ornamental Design for a Combination Coal and Gas Range, of which the following is a specification, reference being had to the accompanying drawing, forming part thereof.

The figure is a perspective view of a combination coal and gas range showing my design.

I claim:

The ornamental design for a combination coal and gas range as shown.

JESSE W. BARKER.
